UNITED STATES PATENT OFFICE.

CHARLES A. DIVINE, OF COLUMBUS, OHIO.

DESIGN FOR A SET OF LETTERS AND NUMERALS FOR SIGNS.

51,259.

Specification for Design.

Patented Sept. 11, 1917.

Application filed May 8, 1916. Serial No. 96,243. Term of patent 14 years.

To all whom it may concern:

Be it known that I, CHARLES A. DIVINE, a citizen of the United States, residing at Columbus, in the county of Franklin and State of Ohio, have invented a certain new, original, and ornamental Design for a Set of Letters and Numerals for Signs, as shown in the accompanying drawings, in which—

Figure 1 is a front elevation of a set of letters and numerals for signs showing my new, original, and ornamental design.

Fig. 2 is an enlarged detail sectional view through one of the letters or numerals.

Fig. 3 is an enlarged detail front elevation showing my new, original and ornamental design.

I claim:

The ornamental design for a set of letters and numerals for signs, substantially as shown.

In testimony whereof I affix my signature in the presence of two witnesses.

CHARLES A. DIVINE.

Witnesses:

O. H. THOMPSON,
S. A. TORRANCE.
